[57] **CLAIM**

The ornamental design for a vehicle windshield wiper unit connector, as shown and described.

DESCRIPTION

FIG. 1 is a rear elevational view of a vehicle windshield wiper unit connector showing my new design it being understood that the front is a mirror image thereof;

FIG. 2 is a top plan view;

FIG. 3 is a bottom plan view thereof;

FIG. 4 is an elevational view looking from the right of FIG. 1, the opposite side being a mirror image thereof; and,

FIG. 5 is a perspective view thereof in an inverted condition.

FIG. 1

FIG. 2

FIG. 3

FIG. 4

FIG. 5
